UNITED STATES PATENT OFFICE.

JOHN A. O'CONNOR, OF CANTON, OHIO.

FUEL ECONOMIZER.

Application filed August 29, 1928. Serial No. 302,703.

The invention relates to a device for use in furnaces of all kinds, and comprises means for preheating air and admitting the same to the combustion chamber of the furnace to facilitate combustion, aiding in the burning of gases which would otherwise pass unburnt to the stack.

The object of the improvement is to provide blocks of refractory material within the combustion chamber adjacent to the grate bars, each block having a vertical opening connected at its lower end to a tube or pipe located beneath the level of the grate bars and extending through the side walls of the furnace; a plurality of cups being located in superposed position within the vertical opening in the block, each cup having an opening in one side of its bottom portion, means being provided for staggering the openings of the various cups with relation to each other so as to slow down the passage of air therethrough in order to heat the air.

An inverted hollow cap may be provided upon the top of each block registering with the uppermost cup therein and provided with a plurality of apertures facing toward the interior of the combustion chamber.

A further object of the improvement is to provide blocks as above described, substantially surrounding the grate bars, and to locate a tube communicating with the atmosphere and extended through the ash pit beneath the grate bars and upward through the central portion of the fire, terminating in a head having a plurality of apertures around the same whereby air is taken into the tube and preheated and passed out over the top of the fire in all directions.

An embodiment of the invention is illustrated in the accompanying drawings, in which

Figure 1 is a vertical sectional view through the ash pit and combustion chamber of a furnace provided with the improved fuel economizer;

Fig. 2, an enlarged top plan view of one of the refractory blocks;

Fig. 3, a plan sectional view through the combustion chamber shown in Fig. 1, parts being broken away for the purpose of illustration; and

Fig. 4, an enlarged detail perspective view of one of the cups.

Similar numerals refer to similar parts throughout the drawings.

A portion of a rectangular furnace is illustrated conventionally, the walls being shown generally at 1, the combustion chamber at 2 and the ash pit at 3. The usual firing door 4 may be provided for charging fuel onto the grate bars 5 and the usual clean-out door 6 may be provided for the ash pit.

The recuperative blocks indicated generally at 7 are adapted to be supported adjacent to the grate bars upon shelves as indicated at 8 which are mounted upon piers or the like as shown at 9.

These blocks may entirely surround the grate bars as illustrated in the drawings in order to obtain the maximum benefit of the invention although a single row of these blocks at one side or end of the grate bars will produce beneficial results.

Each block is formed of suitable refractory material, having the central vertical opening 10 therein registering with the corresponding opening 11 in the shelf 8.

A tube in the form of a coil 12 extends upward through the opening 11 and into the lower end of the central opening 12 of each block as indicated at 13, said tube extending outward through the side wall of the furnace as shown at 14 where it is open to the atmosphere.

The central opening 10 of each recuperative block is shouldered, as shown at 15, at a point spaced from the lower end, providing an enlargement of the opening as shown at 16 extending from the shoulder to the upper end of the block. This enlarged portion of the opening is provided with a plurality of spaced angularly disposed vertical grooves 17.

A plurality of substantially cup-shaped recuperative tiles 18 are adapted to be arranged in superposed position within the enlarged portion 16 of the opening in the block, extending from the shoulder 15 to a point above the top of the block 7.

Each of these tiles has substantially one-half of its bottom wall cut away, forming a half-round opening as shown at 19. A vertical rib 20 is formed upon the outside of each of these recuperative tiles for engagement in any one of the grooves 17 of the block.

In locating these tiles within the block 7,

the openings 19 in the bottoms of the tiles may be staggered with reference to each other as indicated in Fig. 1. By mounting the rib 20 of different ones of the tiles in different grooves 17, any desired arrangement of the openings in the tiles, with reference to each other, may be produced.

By thus staggering the openings in the various tiles with reference to each other, it will be seen that a tortuous passage is provided through the tiles, thus retaining the air for a longer period as it passes through the recuperative block, causing a preheating of the air before it is discharged from the block.

A cap 21, also of suitable refractory material, is placed upon the top of each block. This cap is provided with a central cylindrical opening 22 extending through the bottom 20 of the cap and adapted to fit over the uppermost tile which protrudes above the top of the block 7.

For the purpose of holding the blocks and caps in alignment, each block may be formed 25 at its side edges with tongues and grooves as indicated at 23 and 24, respectively, and the caps may be provided with similar tongues and grooves as shown at 25 and 26, respectively.

30 A plurality of reduced apertures 27 are provided through the inner face of each cap communicating with the central chamber 22 thereof.

With this construction air is drawn in 35 from the outside of the furnace through the coil tubes 12 and recuperative blocks 7, passing upward through the tiles thereof and being preheated throughout the tubes and tiles as it passes through a tortuous passage 40 from the time it enters the tubes.

This preheated air is discharged from the apertures 27 of the various caps into the interior of the combustion chamber, producing a substantially perfect combustion and 45 consuming the gases and a considerable amount of the smoke which would otherwise pass unburnt to the stack.

The preheated air is adapted to enter the combustion chamber just above the flame, 50 mixing with the hot gases to produce perfect combustion. By so doing, the flames are drawn toward the blocks 7, relieving the grate bars from the intense heat of the fire.

55 If it is desired to increase the results above described, a tube 28 may be located through the ash pit directly beneath the grate bars, the outer end thereof registering with an opening 29 in the clean-out door 6.

60 The inner end of this tube may be extended up vertically through the center of the grate as indicated at 30 and provided with a head 31 located just above the hot coals of the fire. This head is provided with 65 a plurality of radial apertures 32 for dis-

charging the heated air from the tube across the fire from the center toward every side of the furnace.

A butterfly valve 33 may be provided at the inlet end portion of the tube 28 and arranged to be operated as by a lever 34 extended through a suitable opening in the clean-out door. When it is desired to open the firing door 4, this butterfly valve may be closed in order to cut off the admission of air 75 to the tube at this time.

If desired, any suitable means may be provided for automatically closing the butterfly valve when the firing door is opened and for opening the valve when the door is 80 closed.

The blocks 7 may be formed sufficiently thick toward the inside of the furnace to prevent breaking or cracking of the same by contact of a poker or the like in firing or 85 raking the fire.

From the above it will be seen that means is provided for taking air from outside of the furnace, preheating the air as it is carried through tortuous paths in the coil tubes 90 and recuperative tiles and discharging the preheated air into the combustion chamber where it mixes with the hot gases to produce perfect combustion.

It should be understood that this invention is applicable to any kind of furnace fire box for either high or low pressure, boilers, 95 locomotives, kilns and all types of furnace fire boxes in general.

I claim:

1. In a furnace having a combustion chamber and a grate therein, a recuperative block located within the combustion chamber adjacent to the grate and having a vertical opening therein, a tube communicating 105 with the lower end of said opening and extended through a wall of the furnace, cup-shaped tiles within said opening each having an opening in one side of its bottom wall and a cap upon the top of the block having 110 a plurality of openings directed over the grate and communicating with the central opening of the block.

2. In a furnace having a combustion chamber and a grate therein, a recuperative block located within the combustion chamber adjacent to the grate and having a vertical opening therein, a coil tube communicating with the lower end of said opening and extended through a wall of the furnace, cup-shaped tiles within said opening each having an opening in one side of its bottom wall and a cap upon the top of the block having a plurality of openings directed over the grate and communicating 115 with the central opening of the block.

3. In a furnace having a combustion chamber and a grate therein, a recuperative block located within the combustion chamber adjacent to the grate and having a ver-

tical opening therein, a tube communicating with the lower end of said opening and extended through a wall of the furnace, cup-shaped tiles within said opening each having an opening in one side of its bottom wall, the openings in said tiles being staggered with relation to each other, and a cap upon the top of the block having a plurality of openings directed over the grate and communicating with the central opening of the block.

4. In a furnace having a combustion chamber and a grate therein, a recuperative block located within the combustion chamber adjacent to the grate and having a vertical opening therein, a tube communicating with the lower end of said opening and extended through a wall of the furnace, cup-shaped tiles within said opening each having an opening in one side of its bottom wall, the openings in the tiles being located at angles to each other, and a cap upon the top of the block having a plurality of openings directed over the grate and communicating with the central opening of the block.

5. In a furnace having a combustion chamber and a grate therein, a recuperative block located within the combustion chamber adjacent to the grate and having a vertical opening therein, a coil tube communicating with the lower end of said opening and extended through a wall of the furnace, cup-shaped tiles within said opening each having an opening in one side of its bottom wall, the openings in said tiles being staggered with relation to each other, and a cap upon the top of the block having a plurality of openings directed over the grate and communicating with the central opening of the block.

6. In a furnace having a combustion chamber and a grate therein, a recuperative block located within the combustion chamber adjacent to the grate and having a vertical opening therein, a coil tube communicating with the lower end of said opening and extended through a wall of the furnace, cup-shaped tiles within said opening each having an opening in one side of its bottom wall, the openings in the tiles being located at angles to each other, and a cap upon the top of the block having a plurality of openings directed over the grate and communicating with the central opening of the block.

7. In a furnace having a combustion chamber and a grate therein, a recuperative block located within the combustion chamber adjacent to the grate and having a vertical opening therein, a tube communicating with the lower end of said opening and extended through a wall of the furnace, cup-shaped tiles within said opening each having an opening in one side of its bottom wall, a cap upon the top of the block having a

plurality of openings directed over the grate 65 and communicating with the central opening of the block, the central opening in the block having a plurality of spaced vertical grooves and a rib upon each tile arranged to be received in any one of said grooves. 70

8. In a furnace having a combustion chamber and a grate therein, a recuperative block located within the combustion chamber adjacent to the grate and having a vertical opening therein, a coil tube communicating with the lower end of said opening and extended through a wall of the furnace, cup-shaped tiles within said opening each having an opening in one side of its bottom wall, a cap upon the top of the block having a plurality of openings directed over the grate and communicating with the central opening of the block, the central opening in the block having a plurality of spaced vertical grooves and a rib upon each tile arranged to be received in any one of said grooves. 75

9. In a furnace having a combustion chamber and a grate therein, a recuperative block located within the combustion chamber adjacent to the grate and having a vertical opening therein, a tube communicating with the lower end of said opening and extended through a wall of the furnace, cup-shaped tiles within said opening each having an opening in one side of its bottom wall, the uppermost tile protruding above the top of the block, and a hollow cap fitting over said uppermost tile and having a plurality of openings directed over the grate. 90

10. In a furnace having a combustion chamber and a grate therein, a recuperative block located within the combustion chamber adjacent to the grate and having a vertical opening therein, a coil tube communicating with the lower end of said opening and extended through a wall of the furnace, cup-shaped tiles within said opening each having an opening in one side of its bottom wall, the uppermost tile protruding above the top of the block, and a hollow cap fitting over said uppermost tile and having a plurality of openings directed over the grate. 105

11. In a furnace having a combustion chamber and a grate therein, a recuperative block located within the combustion chamber adjacent to the grate and having a vertical opening therein, cup-shaped tiles within said opening each having an opening in one side of its bottom wall and a cap upon the top of the block having a plurality of openings directed over the grate and communicating with the central opening of the block. 115

12. In a furnace having a combustion chamber and a grate therein, a recuperative block located within the combustion chamber adjacent to the grate and having a vertical opening therein, cup-shaped tiles with-

in said opening each having an opening in one side of its bottom wall, the openings in said tiles being staggered with relation to each other, and a cap upon the top of the block having a plurality of openings directed over the grate and communicating with the central opening of the block.

13. In a furnace having a combustion chamber and a grate therein, a recuperative block located within the combustion chamber adjacent to the grate and having a vertical opening therein, cup-shaped tiles within said opening each having an opening in one side of its bottom wall, the openings in the tiles being located at angles to each other, and a cap upon the top of the block having a plurality of openings directed over the grate and communicating with the central opening of the block.

20 14. In a furnace having a combustion chamber and a grate therein, a recuperative block located within the combustion chamber adjacent to the grate and having a vertical opening therein, cup-shaped tiles within said opening each having an opening in one side of its bottom wall, a cap upon the top of the block having a plurality of openings directed over the grate and communicating with the central opening of the block, the central opening in the block having a plurality of spaced vertical grooves and a rib upon each tile arranged to be received in any one of said grooves.

35 15. In a furnace having a combustion chamber and a grate therein, a recuperative block located within the combustion chamber adjacent to the grate and having a vertical opening therein, cup-shaped tiles within said opening each having an opening in one side of its bottom wall, the uppermost tile protruding above the top of the block, and a hollow cap fitting over said uppermost tile and having a plurality of openings directed over the grate.

45 16. In a furnace having a combustion chamber and a grate therein, recuperative blocks located within the combustion chamber and surrounding the grate, each block having a vertical opening therein, cup-shaped tiles within said opening each having an opening in one side of its bottom wall and a cap upon the top of each block having a plurality of openings directed over the

grate and communicating with the central opening of the block.

55 17. In a furnace having a combustion chamber and a grate therein, recuperative blocks located within the combustion chamber and surrounding the grate, each block having a vertical opening therein, cup-shaped tiles within said opening each having an opening in one side of its bottom wall, a cap upon the top of each block having a plurality of openings directed over the grate and communicating with the central opening of the block, and a tube located beneath the grate and communicating with the outside atmosphere, the inner end of the tube extending upward through the center of the grate and provided with a head spaced above the grate and having apertures around its periphery.

60 18. In a furnace having a combustion chamber and a grate therein, recuperative blocks located within the combustion chamber and surrounding the grate, each block having a vertical opening therein, cup-shaped tiles within said opening each having an opening in one side of its bottom wall, a cap upon the top of each block having a plurality of openings directed over the grate and communicating with the central opening of the block, a tube located beneath the grate and communicating with the outside atmosphere, the inner end of the tube extending upward through the center of the grate and provided with a head spaced above the grate and having apertures around its periphery, and a valve in said tube.

65 19. In a furnace having a combustion chamber and a grate therein, recuperative blocks located within the combustion chamber and surrounding the grate, each block having a vertical opening therein, a tube communicating with the opening in each block and extended through a wall of the furnace, cup-shaped tiles within said opening each having an opening in one side of its bottom wall and a cap upon the top of each block having a plurality of openings directed over the grate and communicating with the central opening of the block.

70 In testimony that I claim the above, I have hereunto subscribed my name.

JOHN A. O'CONNOR.
